UNITED STATES PATENT OFFICE.

WILLIAM E. ELAM, OF AMERICUS, GEORGIA.

DEVICE FOR STRINGING AND FILING PAPERS.

SPECIFICATION forming part of Letters Patent No. 350,976, dated October 19, 1886.

Application filed December 22, 1885. Serial No. 186,457. (No model.)

To all whom it may concern:-

Be it known that I, WILLIAM E. ELAM, a citizen of the United States, residing at Americus, in the county of Sumter and State of Georgia, have invented certain new and useful Improvements in Devices for Stringing and Filing Papers; and I do hereby declare that the following is a full, clear, and exact description of the same, reference being had to the annexed drawings, making a part of this specification, and to the letters and figures of reference marked thereon.

Figure 1 of the drawings is a perspective view of my invention, and Figs. 2 and 3 modifications thereof.

The present invention has relation to certain new and useful improvements in devices for stringing and filing papers, and relates more particularly to that class for which a patent was granted to me August 5, 1884, No. 302,989; and it consists in the details of construction, substantially as shown in the drawings and hereinafter described and claimed.

In the accompanying drawings, A represents a suitable bracket for attaching to a wall or other object, said bracket having a horizontally-extending arm, B, of any preferred form. This arm B, at its outer extremity, terminates in a suitable hooked end, *a*, and the arm is also provided with a suitable latch, C, pivoted thereto, and its forward end engaging with the hooked end *a*, as shown. A small pin, *b*, on the arm B supports the latch C, and prevents it falling down below the arm. The latch can be raised to the desired height to disengage the end thereof, as shown in dotted lines, Fig. 2.

In place of the bracket A, the arm B may be connected to or formed on the end of a suitable standard, and provided with an upright extension, *c*, for attaching thereto a swinging wire guard, D, as in my former patent, to prevent the papers from working off the wire E. This wire is preferably pointed at its upper end, and its opposite end formed tubular or with a socket for fitting over the end of a wire or needle, F, which is held in the hooked end *a* by the pressure of the end of the latch C against the wire or needle. The wire or needle F has an eye at one end for attaching a cord, G, which is passed through the eye, and its ends suitably connected to a cross-bar, *d*.

If preferred, the wire E may be made tubular throughout its length, and when in position, as shown in Fig. 1, the papers are placed thereon and pushed down below the pivoted or swinging guard D. If at any time a certain paper is required to be withdrawn without tearing it, all the papers above the one desired are pushed up on the wire E, the remaining ones being on the wire or needle F. The wire E is now detached from the needle or wire F, which will admit of the removal of the paper required, the needle or wire being held firmly in an upright position by the latch C. When the wire or needle F is filled with papers, or it is desired to file those that are on it, the wire or needle is removed with the papers, and the latter pushed down onto the cord G, after which the cord is cut and the two ends tied together, thereby providing a device simple in construction, and in which certain papers can be removed without disturbing others, and reducing the labor necessary for permanently stringing them after the file has been filled or provided with the desired number of papers.

To enable the clamping or holding device, which consists of the hooked arm B and pivoted latch C, being supported on a disk or table, I provide it with a horizontal bracket, H, as shown in Fig. 3, which also shows the cord after being cut with the papers thereon ready for filing, and the needle replaced in the clamping or holding device.

The invention is designed as an improvement upon the device patented to me August 5, 1884, No. 302,989, in which the papers were strung upon a single wire having a cross-piece. In my present device I string the papers on a needle arranged point upward, and to the eye of the needle I attach a wire, thread, or cord having a cross-bar. In such case the needle F may serve with many stringing-wires G.

Having now fully described my invention, what I claim as new, and desire to secure by Letters Patent, is—

1. In a paper-clip, the combination, with a needle or wire, F, and means for supporting it, and with a tubular wire, E, of a stringing cord or wire, G, having a cross-bar, and secured to the eye of the needle, the whole arranged for joint operation as set forth.

2. The combination, with the frame B and latch C, and with the needle F, held by such frame and latch with its point above and eye below, of the tubular wire E, arranged to 5 operate over the point of the needle F, a spring-frame, D, and stringing wire or cord G, having cross-bar or stop d, the wire or cord being passed through the eye of the needle F, and the whole arranged for joint operation as to set forth.

In testimony that I claim the above I have hereunto subscribed my name in the presence of two witnesses.

WILLIAM E. ELAM.
